UNITED STATES PATENT OFFICE.

OSCAR ONSRUD, OF CHICAGO, ILLINOIS, ASSIGNOR TO THE MARBLE AND SHATTUCK CHAIR COMPANY, OF CLEVELAND, OHIO, A CORPORATION OF OHIO.

DOVETAILING-MACHINE.

1,352,620.

Specification of Letters Patent. Patented Sept. 14, 1920.

Application filed March 22, 1920. Serial No. 387,703.

To all whom it may concern:

Be it known that I, OSCAR ONSRUD, a citizen of the United States of America, and a resident of Chicago, county of Cook, and State of Illinois, have invented certain new and useful Improvements in Dovetailing-Machines, of which the following is a specification.

This invention relates to wood working machines, and especially to that type of such machines of semi-automatic character which is adapted for milling operations. The main objects of the invention are to provide such a machine adapted for a special form of dovetailing; to provide for making the necessary cuts for a double dovetailed member such as shown in the drawings; to provide for automatic advancement and tilting of the stock to be worked upon between cuts so as to hold the block in proper position for the respective cuts; to provide an improved form of chuck and controlling mechanism therefor; and to provide improved means for sharpening the gang cutters without removal from the machine.

An illustrative embodiment of this invention is shown in the accompanying drawings, in which—

Figure 1 is a front elevation of the upper part of the machine.

Fig. 2 is a right side elevation of the device shown in Fig. 1.

Fig. 3 is an enlarged longitudinal section through the dog mechanism shown at the left-hand side of Fig. 2.

Fig. 4 is a left side elevation of part of the device shown in Fig. 1, the automatic chuck tilting dog being shown in one of its positions.

Fig. 5 is a vertical cross section through the block after it has been cut and the holding means or chuck therefor in the position for one of the cuts.

Fig. 6 is a similar view, but with the holder and block tilted to its reversed position for the other cut.

Fig. 7 is similar to Fig. 4 except that the automatic dog is shown in a medial position as the block holder or chuck is tilted from one position to the other.

Fig. 8 is similar to Fig. 4 except that the dog is in its reversed position.

Fig. 9 is a longitudinal vertical section

through the chuck and its immediate support or mounting.

Fig. 10 is a perspective view of a wooden blank or block to be cut.

Fig. 11 is a perspective view of the finished block after cutting.

Fig. 12 is a cross section at the line 12—12 on Fig. 9.

Fig. 13 is a cross section at the line 13—13 on Fig. 9.

In the construction shown in the drawings, the machine as a whole comprises the main elements of an ordinary milling machine in combination with certain new and improved attachments hereinafter described, adapting it for the special objects stated. Said machine includes mainly a frame 1 of upright character as usual in milling machines, in combination with a vertically adjustable bed plate 2, a horizontally movable carriage 3 on said plate; a set of gang cutters 4 on the upper part of said frame; a chuck 5 on said carriage to hold the block 6 to be cut, a grinder 7 at the top of said frame for sharpening said cutters, an automatic dog 8 for tilting the chuck between cuts, a manually operated ejector 9 at the opposite end of the chuck from said dog to throw out the blocks after being cut, manual means 10 for raising and lowering the knee 11 supporting the bed plate, as usual in milling machines, manual means 12 to operate the carriage forward and back; and a pulley 13 for supplying power to the cutters as from a belt, not shown.

The chuck 5, though carried by the member 3, is not mounted directly thereon, but is supported on a frame 14 which in turn is secured to the carriage 3 demountably by means of the bolts 15. It is to this carriage and the mechanism connected thereto that this invention mainly relates.

The chuck 5 is of elongated tubular shape and is journaled in said frame 14 in a horizontal position parallel with the gang cutter axis and crosswise of the direction of movement of said carriage. The front end of said chuck is supported in an upstanding bracket 16 on the chuck holding frame and the opposite end is supported by the main body part 14' of said frame, being held demountably by the cap pieces 17 and 18 secured by screws as usual for such purposes.

The part of the chuck between the frame members 14' and 16 is hollow to receive the block 6 to be cut and is provided with a set of transverse slots 19 in one side corresponding in size and spacing with the individual cutter disks 20 of the gang member 4. The opposite end of the chuck is provided with a disk shaped head 21 having a pair of oppositely disposed horizontally projecting parallel pins 22 and 22' to alternately engage the ends of the forked dog member 8, and also an intermediately disposed pin 22" to engage the inner faces of the dog branches 23 in the intermediate positions of the dog, as will be further explained.

The gang cutter 4 comprises a plurality of disks, four in this instance, mounted side by side in spaced relation on the arbor 24 which is rigid with the driving shaft 25 to which the pulley 13 is fixed, whereby they are driven constantly at a high speed, as by a motor not shown.

The grinder 7 is carried adjustably by the lock-pivot 26 on an arm 27 which is mounted swingingly on the upper part of the frame 1, as on a screw-lock pivot 28 and comprises a motor 29 which in this instance is pneumatic, and a downwardly projecting shaft 30 carrying a grinding tool proper 31. The pivot 28 is carried by a supporting carriage 32 slidable parallelly with shaft 25. Hence the grinding tool 31 is capable of adjustable setting in any position in the plane of any disk, and the grinder attachment as a whole is slidable on track 33 to engage any one of the cutter disks.

Said grinder is applicable to either the inner or outer side of each tooth 4'. The disks, 20, are all set with their teeth in horizontal alinement so that, in grinding, it is only necessary to set the angular position of the grinder and then move it forward and back by means of the carriage handle 32'. Compressed air is supplied to the motor 29, through the flexible tube 29'. After the teeth are ground the disks are moved relatively to one another so as to bring the teeth in staggered mutual relation for cutting.

The work holder or chuck 5 is held rigidly against rotation during the cutting process by means of the lock in the form of a plunger 34, fitting alternately in the sockets 35 and 36 in the enlarged head 21 at the left end of the chuck. Said lock is mounted slidably in the vertical aperture 38, in the under side of the frame 14, where it is urged normally upward into engagement with the head 21, by lever 39, actuated by spring 40. Said lever 39 is mounted on the horizontal pivot 41, at the lower end of bracket 42, on said frame 14. Said lever 39 is disposed horizontally in the direction of movement of the carriage 3, and is actuated automatically by the stop 43, mounted on bracket 44, which

is secured at its base to the frame 1, by bolts 45. Said stop 43, is so positioned near the front of the machine that it does not actuate the lever 39, until the carriage has nearly reached its starting point. The spring arm 70 of said lever 39 is formed with a central bearing 46, which rides slidably in the aperture 47, in the lower end of said lock 34. The opposite or stop arm of said lever extends forwardly, that is to say, to the left, 75 as viewed in Fig. 2, and its lower corner is beveled at 48, to register normally with the upper beveled corner 49, of the stop 43, over which it rides as the cam carriage is restored to its normal position and thereby 80 releases said cam for tilting by said dog. Said stop 43 thus serves to tilt the lever 39, and retract the lock 34, against the spring 40, when the carriage returns to its initial position after each cut. 85

The stop member 43, is in the form of an upright arm carried by the pivot bolt 50, at its lower end and is held normally in upright position by means of spring 51, a stop shoulder 52 being provided on the bracket 90 44, to arrest said stop as it swings to its vertical position. The lever 39 is recessed back of the bevel corner 48, as at 53, so that when the carriage and chuck supported thereon are retracted to their normal position, the 95 lever 39, will be free to act under the influence of spring 40 to force the lock 34 into its effective locking relation with said chuck. Then when the carriage advances for the next cut, the lever shoulder 54, is released 100 by stop 43, which swings against the tension of spring 51. The chuck, therefore, as it is moved bodily on said carriage, remains locked against rotation until it reaches that point in the return of the carriage where the 105 beveled lever face 48, meets the beveled stop face 49, whereupon the lock is released sufficiently to permit oscillation of the chuck by the dog 8.

The chuck 5, though having a substantially cylindrical character as a whole, is somewhat irregular, being provided with an enlargement or protuberance 55, on its lower side at the work receiving end to accommodate the clamping wedge 56, and the guide 110 means 57, therefor. Said chuck on the opposite side of its medial bearing part 58, is provided with a spiral cam projection 59, somewhat resembling a screw thread which fits in the corresponding cam slot of 60, of 115 the adjacent bearing part 14'. The opposite end of said chuck from the work-holding end is hollow as at 61, and is provided with an axially disposed ejector plunger 62, having a handle 63. Said ejector is provided with 120 a head 64, at its inner end to bear against the work in the chuck and to limit the outward movement of the ejector under the action of compression spring 65. One end of said spring is seated against the inner end 66, of 125 130

chamber 61, and the outer end bears against the shoulder 67, on said ejector.

In order to facilitate ready manual control of the wedge 56, a handle 68, is provided therefor, including a shaft 69, extending through an aperture 70 in the front wall 71 of the chuck below the main opening 72, through which the stock is admitted and ejected. In order to seat the wedge 10 tightly against the material to be cut, the handle 68 is first thrust in manually and may then be tapped lightly with a mallet. When the work is to be removed, the wedge is loosened by pulling outward on the handle, 15 68.

In operating the dove-tailing machine above described, the first step, after having adjusted the height of the knee 11, and secured the gang cutter 4, in place, is to insert 20 a block 6 in the chuck 5, the carriage being in its retracted position, namely, to the left, as shown in Fig. 2. Then, the cutter being 25 in operation, speeded preferably at about 4000 R. P. M., the handle 12, is turned to advance the carriage 3, and mechanism carried thereby, so as to engage the cutters with said block.

The handle 12, is then turned backward, whereby the carriage is restored to its initial 30 position and at the same time the chuck is engaged by the dog 8, controlled by lever 39, whereby it is rotated in this instance 90°, and at the same time the chuck is thereby advanced a distance equal to the thickness 35 of the dove-tail tenons by means of the spiral cam 59, ready for the second cut. The handle 12 is again operated to advance and retract the carriage. In so doing, the dog 8, reverses the tilt of the chuck, that is to say, 40 restores it, and thereby causes the cam to slide the chuck with its finished block back to its initial position. The dovetailed block is then ejected by an inward thrust of the hand against the handle 68, the 45 clamping means 56, having first been released.

Referring more in detail to the precise operation of the chuck tilting means 8, it is to be noted that normally, that is to say, 50 when the machine is in its initial position ready to receive work to be operated upon, the dog 8, is in the position shown in the right and left side views, Figs. 2 and 4, respectively.

55 In this position the shank part 73, is inclined upward and the two arms 23 and 23' are correspondingly inclined downward, the inclination being limited by the fixed stop pin 74, on the rigidly mounted bracket 75, 60 which is held adjustably by bolt 76 to the main frame 1, of the machine. Said pin fits in the arcuate slot 77, in the shank 73, so as to permit limited tilting of the dog on its pivot 78. Said dog is yieldingly urged 65 to the limits of its range of oscillation by the

spring actuated means 79, supported on pivot 80, which is carried by the same bracket as pin 74, but nearer the outer end thereof, as shown in Fig. 4.

The member 79, comprises a flat frame 76 81, the outer end 82, of which is turned inward at a right angle, and provided with a plunger 83. The end of said plunger projects through a hole 82' in the end 82, which serves as a centering means or bearing for 75 the plunger. Said plunger is provided with a head 84 between which and the guide member 82, is mounted a compression spring 85, which urges the plunger toward the dog 8. The headed end of the plunger 80 is, if pivoted at 83', to the free end of the dog shank 73, in substantially toggle relation thereto, so as to provide a snap-over action when the dog is oscillated by coaction with the chuck shoulders 22, 22' and 22''. Said frame is provided with a slot 81' in which slides the extended end of pivot 83', whereby said frame 81, and plunger 83, are held in parallel relation.

In the initial forward movement of the 90 carriage, referring now to Figs. 4 and 7, the lower side of the upper dog arm 23, slidingly engages the medial pin 22' on the chuck head 21, whereby the forked end of the dog is raised sufficiently to throw the shank 73, downward beyond its neutral position of alinement with pivot 80, whereupon it will automatically snap over to the position shown in Fig. 8, where the movement of the dog is arrested by the stop pin 74, bearing against the upper end of the slot 77. In this movement, the plunger 83, is forced outward against the tension of spring 85 and is then restored by the spring as the dog takes its new position, shown in Fig. 8. 95 100 105

Upon the return of the carriage after the first cut, the lock 34, is released by means 39 and 43, and then the lower pin 22' on the chuck head 21, is arrested by the squarely opposing end of dog arm 23', whereby the 110 chuck is tilted, as will be understood by reference to Fig. 8, where, as will be seen, further movement of the carriage to the right, as in restoring to its initial position, will cause the arm 23', acting against pin 22', to 115 effect the desired tilting of the chuck preparatory for the next forward movement.

Simultaneously with the latter part of the 120 said return movement of the carriage the lever 39, (see Fig. 8), serves to release the lock 34, preparatory for the chuck oscillation. As the chuck oscillates, in this instance, 90°, referring still to Fig. 8, it will be seen that pin 22'' will be swung down back of the lower arm 23'. Then upon the 125 next movement forward of the carriage, the pin 22'' will slidably engage the upper or inner side of arm 23' and tilt the dog shank 73 upward past the critical point, whereupon it will snap back to the position shown in 130

Fig. 4. The chuck is held against rotation during the dog tilting operation by means of the lock 34, which is then in its effective position.

5 When the carriage is restored to its initial position after its second movement forward, the upper pin 22 will bear against the end of chuck arm 23, the lock 34, having been released, and the chuck will be restored to its 10 initial position, shown in Fig. 4, ready for ejection of the finished work and reception of a new blank or block to be cut.

The machine herein specifically described is especially adapted for milling the dovetail recesses in such blocks as are described in the Foote Patent No. 1,303,646, dated May 12, 1919.

Although but one specific embodiment of this invention is herein shown and described, 20 it is to be understood that numerous details of the construction shown may be altered or omitted, without departing from the spirit of the invention, as defined by the following claims:

25 I claim:

1. In a machine of the character described, automatic chuck tilting means comprising a forked dog pivoted centrally, a resilient compression member pivotally connected to the free end of the shank of said dog and with its opposite end mounted turnably at a point opposite the end of said shank and spaced therefrom, the arms of said dog being formed and adapted to successively engage suitably formed shoulders on the chuck when the latter is moved forward and backward relative to said dog.

2. A wood working machine comprising a frame in combination with an oscillatingly 40 mounted chuck, a cutter in operative relation to work held in said chuck, and automatic means respectively for oscillating the chuck and simultaneously advancing same transversely of the path of main relative 45 movement of the cutter and chuck.

3. In a milling machine adapted for a plurality of automatically controlled successive operations and having a horizontally reciprocating carriage and a tool arbor disposed transversely over the path of said carriage, a frame fixed on said carriage and a cutter fixed on said arbor, said frame having a horizontally disposed elongated hollow chuck movable lengthwise and rotatably and extending crosswise of the direction of carriage movement to hold the work to be acted upon by said cutter, and automatic means to move said chuck including a cam to reciprocate the chuck lengthwise and a pivotally mounted and spring-actuated forked 50 dog on the main frame of the machine with a plurality of shoulders arranged on said chuck to operatively coact in due succession with the arms of said dog as said carriage moves relative to said dog, so as to move the 55 chuck from its one position to another for successive cuts on the work held by said chuck.

4. In a dovetailing machine adapted for a plurality of automatically controlled successive operations, having a horizontally reciprocating carriage and a power gang tool disposed over the path of said carriage, and a frame fixed on said carriage, said frame having a horizontally disposed elongated 70 hollow chuck extending crosswise of the direction of carriage movement, and automatic means to oscillate said chuck including spring-actuated dog on the main frame of the machine and a plurality of shoulders 75 arranged on said chuck to operatively coact in due succession with said dog as said carriage moves relative to said dog so as to turn the chuck from its one position to another 80 for successive kerf cuts on the work held by said chuck.

Signed at Chicago this 18 day of March, 1920.

OSCAR ONSRUD.
